CLAIM

The ornamental design for a spray gun, as shown and described.

DESCRIPTION

FIG. 1 is a front, right and top perspective view of a spray gun, showing my new design;
 FIG. 2 is a rear, left and bottom perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof;
 FIG. 8 is a bottom plan view thereof; and,
 FIG. 9 is an enlarged view of portion of FIG. 1 thereof.
 The broken lines shown in the drawings illustrate portions of the spray gun that form no part of the claimed design.
 The dot-dash broken lines in FIGS. 1 and 9 are for annotating the enlarged views only and form no part thereof.

1 Claim, 9 Drawing Sheets(56)
